UNITED STATES PATENT OFFICE

ALBERT W. MENNS, OF MELDEN, MASSACHUSETTS, ASSIGNOR, BY DIRECT AND MESNE ASSIGNMENTS, TO MENNS WINDOW CORPORATION, OF BOSTON, MASSACHUSETTS, A CORPORATION

WINDOW CONSTRUCTION

Application filed February 18, 1930. Serial No. 429,305.

This invention relates to improvements in window construction, and particularly in the type of window construction having upper and lower sashes sliding in parallel planes. 5 Still more specifically, this invention relates to improvements in the type of window construction having upper and lower sashes sliding in parallel planes, wherein the sashes are pivoted upon riders and can be displaced 10 angularly from their planes of sliding.

The primary object of this invention is to provide a novel form of window construction wherein the sashes, pivotally mounted upon riders slidable in the stile grooves of 15 the window frame, automatically lock the riders in their stile grooves at any given elevation or position when the sashes are displaced angularly from their planes of sliding, thus arresting any tendency to movement 20 of the riders caused by the pull upward upon the riders of the partially unbalanced sash weights. Another object of this invention is to provide window construction of the aforesaid character, wherein the sashes can be entirely detached from their riders, so permitting the repairing of the sashes, the cleaning 25 of the outside faces of the window panes, the installing of outside screens, and the passing of large objects such as furniture through 30 the window to be accomplished with ease. Another object of this invention is to provide window construction of the aforesaid character, wherein both sashes however greatly displaced angularly from their planes 35 of sliding are never in interference with outside screens or shutters. Another object of this invention is to provide window construction of the aforesaid character which is adequately waterproof, draftproof and burglar- 40 proof. Another object of this invention is to provide riders and means for locking these riders in their stile grooves at any given elevation or position by angular displacements 45 of the sashes pivoted upon these riders, adaptable to the present type of window frames and sashes, so that the installation of pivoted detachable sashes in the window frames of existing houses can be effected inexpensively and in a simple manner by 50 making slight alterations in the construction

of the window frames and of the sashes now in use.

The realization of these and of other objects by this invention can best be realized and appreciated by an examination of the following description and the accompanying drawings wherein a particular embodiment 55 of this invention is described and illustrated. The scope of the invention is defined in the appended claims. 60

Referring now to the drawings in which similar numerals are used to designate corresponding parts throughout the several views and primed numerals are used to designate similar parts generally not shown in the views: 65

Figure 1 is a view in perspective of the improved window construction showing the lower sash displaced angularly from its plane of sliding to an extent greater than ninety 70 degrees, and the upper sash completely detached from its riders.

Figure 2 is a view in cross section of the closed window along the line 2—2 of Figure 1, showing the left-hand portion of the window frame and portions of the sashes and of their riders in their planes of sliding. The view of the portion of the upper sash and of its rider is in cross section, while that of the portion of the lower sash and of its 75 rider is an external one. 80

Figure 3 is a view in perspective of the right-hand lower corner of the lower sash showing the design of the pivot bearing plate to which reference will later be made. 85

Figure 4 is a side elevational view partly sectional, and also partly cross sectional of the left rider of the lower sash, in which are shown the pivot, the mechanism for locking the rider in its stile groove, together with the notched structure of the stile groove with which the locking mechanism engages, and the slot which acts as a catch for the left-hand spring bolt upon the top of the lower sash. This spring bolt 90 and catch together with the pivot and pivot bearing serve to hold the sash and its rider united in their plane of sliding. 95

In the drawings, 1 designates the window frame of the ordinary type, consisting of left- 100

hand and right-hand jambs, cross head, sill, and stiles, with the stile grooves somewhat modified as will be described. The lower sash 2 is mounted upon the lefthand lower rider 4 and its counterpart 4' the right-hand lower rider, by means of the pivots 12 and 12' and the pivot bearings 13 and 13', and is held in the plane of sliding by the spring bolts 14 and 14' engaging with the slots 10 and 10'. 10 Similarly, the upper sash 3 is mounted upon the left-hand upper rider 5 and its counterpart 5' the right-hand upper rider, by means of similar pivots and pivot bearings, and is held in its plane of sliding by the spring bolts 15 and 15' engaging with the slots 11 and 11'.

The pair of riders 4 and 4' a cross sectional view of which is shown in Figure 4 are here constructed of wood faced with the metal plates 21 and 21' provided with the slots 10 and 10', and pivots 12 and 12'. These riders are longitudinally grooved as is shown at 35 to take the guide plates 16 and 16' set into the sash guides 7 and 7' and extending the 20 full length of the stile grooves. These guide plates are provided with notches or teeth 33 and 33' with which the catch bolts 28 and 28' set into the grooves 34 and 34' and actuated by the spring assemblies 25 29 and 36 and 29' and 36' respectively engage, and thereby prevent any upward movement 30 of the riders. When these arresting mechanisms are disengaged by the coactions of the 35 riders and sash through the agencies of the catch pins 9 and 9' working in the slots 8 and 8', the riders slid in the stile grooves of the window frame, being retained therein by the 40 guide plates 16 and 16' and the parting beads 6 and 6'. These riders are rabbeted throughout their lengths to receive the sashes, which are rabbeted inversely or complementarily as is shown in Figure 2 and in Figure 3.

Similarly, the pair of riders 5 and 5' a cross sectional view of which is shown in Figure 4 are here constructed of wood faced with metal plates provided with slots and pivots, are longitudinally grooved to take the guide plates 17 and 17' mounted upon and screwed to the parting beads 6 and 6' extending the 45 full length of the stile grooves, and are provided with catch bolts actuated by spring assemblies to engage with the notches or teeth of the guide plates to prevent any upward movement of the riders. When these arresting 50 mechanisms are disengaged by the coactions of the riders and sash through the agencies of the catch pins working in their slots, the riders slide in the stile grooves of the window frame, being retained therein by the 55 guide plates 17 and 17' and the external sash guides 20 and 20'. These riders too are rabbeted throughout their lengths to receive the sashes which are rabbeted inversely or complementarily as is shown in Figure 2. 60 The riders 5 and 5' are considerably thicker 65

than are the riders 4 and 4', for a certain amount of clearance for the tilting of sash 3 is required as an examination of Figure 2 will disclose.

The lower sash 3, somewhat narrower than 70 is the standard sash supplied with the window frame but not otherwise different, is just sufficiently wide to fit snugly between its riders 4 and 4'. It is rabbeted longitudinally along the rear edges of the sides and bears on 75 its sides at the lower edges the two pivot bearing plates 32 and 32'. The pivot bearings are continued into slots 30 and 30' to take the flattened pivots 12 and 12' at an angle somewhat less than ninety degrees. The pivot 80 bearing plates and the rabbets are given the rounded off shapes illustrated at 31 of Figure 3 to permit the rotation of the sash upon its pivots. The two spring bolts 14 and 14' with the glass 26, the glass retaining strip 25, and one part of the window catch 18, complete the 85 lower sash ensemble.

The upper sash 4, somewhat narrower than 90 is the lower sash, and of course considerably narrower than is the standard sash supplied 95 with the window frame, but not otherwise different, is just sufficiently wide to fit snugly between its riders 5 and 5'. This sash, rabbeted longitudinally along the rear edges of the sides, is fitted with bearing plates in a 100 manner similar to that of the lower sash. The two spring bolts 15 and 15', with the glass and glass retaining strip, and the other part of the window catch 19, complete the 105 upper sash ensemble.

The lower and upper sash ensembles when suspended in the stile grooves of the window frame are balanced by the window weights 22 and 22' connected to the riders by means of the sash cords 23 and 23' passing over the 110 sheaves 24 and 24'.

It is obvious that the lower and upper sashes of this improvement in window construction can be made from the sashes supplied with the ordinary type of window 115 frame by a few simple alterations.

The guide plates 16, 16', 17, and 17' serve also as weather stripping and when used in the common double check rail window render it substantially air tight.

The operation of the invention is as follows: upon the release of the spring bolts 14 and 14' of the lower sash 2, the lower sash can be rotated about its pivots, allowing in its initial slight angular displacement the catch bolts 28 and 28' to engage in the notches or teeth 33 and 33' of the guide plates 16 and 16', thus locking the riders in their stile grooves and arresting any tendency to movement of the riders 4 and 4' caused by the pull on the riders of the partially unbalanced window weights. The sash can be rotated about its pivots to the angle of detachment and it can then be completely removed from its 120 riders, or it can be rotated until it makes 125 130

contact with the sill while still hanging from its riders, and in such position permits the outside face of the window glass to be cleaned. Similarly, the upper sash can be rotated upon its pivots and detached from its riders, or it can be rotated until it makes contact either with the hanging lower sash, or, if the lower sash has been detached, with the sill, and in such position permits the outside 10 face of the window glass to be cleaned. Reversal of the order of these operations serves to reassemble the sashes in the window frame.

While the present embodiment of the invention has been described in detail, both as to materials and as to construction, the protection of all possible modifications of materials and of construction within the spirit and scope of the invention as defined in the appended claims is sought. Thus, the invention is applicable to sashes and to riders made wholly or in part of wood or of metal. And the arresting mechanisms may take any form consonant with their function of locking the riders in their stile grooves through 25 the coaction of the sashes and riders.

Having described my invention and its operation, I claim:

1. In combination, a window frame having stile grooves for sliding sashes, sashes mounted upon riders slidable in the stile grooves, means for locking the sashes to the riders, and cooperating means borne by the riders and the window frame for locking positively against upward movement the 35 riders in the stile grooves at various elevations comprising latch means and integral members adapted at points spaced throughout their lengths to engage with the latch means.

2. In combination, a window frame having stile grooves for sliding sashes, sashes mounted pivotally upon riders slidable in the stile grooves, means for locking the sashes to the riders, and cooperating means operatively controlled by angular displacement of the sashes upon the riders for locking positively against upward movement the riders in the stile grooves at various elevations comprising latch means borne by the 50 riders and integral members borne by the window frame and adapted at points spaced throughout their lengths to engagingly receive the latch means.

3. In combination, a window frame having stile grooves for sliding sashes, sashes mounted pivotally upon riders slidable in the stile grooves, means for locking the sashes to the riders, and means for locking 55 positively against upward movement the riders in the stile grooves at various elevations comprising spring actuated latches borne by the riders and operatively controlled by angular displacement of the sashes upon the riders, and strips borne by

the window frame and provided with recesses wherein to receive the latches.

4. In combination, a window frame having stile grooves for sliding sashes, sashes mounted pivotally upon riders slidable in the stile grooves, means for locking the sashes to the riders, and means for locking positively against upward movement the riders in the stile grooves at any one of a series of positions spaced apart equidistantly throughout the paths of the riders comprising spring 70 actuated latches borne by the riders and operatively controlled by angular displacement of the sashes upon the riders, and strips borne by the window frame parallel to the stile grooves and provided with serrations spaced apart equidistantly throughout substantially their lengths wherein to receive the latches.

5. In combination, a window frame having stile grooves for sliding sashes, sashes mounted pivotally upon and instantaneously detachable only at a given angle of the sashes to the riders from riders slidable in the stile grooves, and means for locking the sashes to the riders.

6. In combination, a pair of riders slidable in opposed stile grooves of a window frame, each of the said riders carrying a pivot whose bearing surface is parallelly flattened, a sash carrying bearing plates slotted to slidably receive the parallelly flattened bearing surfaces to seat the pivots in their bearings upon translation of the sash at a given angle only of its plane to the plane of the riders, and means for locking the sash to the riders.

In testimony whereof, I affix my signature.

ALBERT W. MENNS.
